Primary Examiner — Wendy L Arminio(74) *Attorney, Agent, or Firm* — Collard & Roe, P.C.(57) **CLAIM**

The ornamental design for an aerosol actuator, as shown and described.

DESCRIPTION

FIG. 1 is a front, left side and top perspective view of an aerosol actuator, showing my new design;

FIG. 2 is a front view thereof;

FIG. 3 is a left side view thereof;

FIG. 4 is a right side view thereof;

FIG. 5 is a rear view thereof;

FIG. 6 is a top view thereof; and,

FIG. 7 is a bottom view thereof.

The broken line and the region shown within it depict portions of the aerosol actuator that forms no part of the claimed design.
